UNITED STATES PATENT OFFICE

WILLIAM T. BRADBURY, OF KANKAKEE, ILLINOIS, ASSIGNOR TO FLORENCE STOVE COMPANY, OF BOSTON, MASSACHUSETTS, A CORPORATION OF MASSACHUSETTS

DESIGN FOR A GAS STOVE

Application filed December 14, 1931. Serial No. 42,071. Term of patent 7 years.

To all whom it may concern:

Be it known that I, WILLIAM T. BRADBURY, a citizen of the United States, residing at Kankakee, in the county of Kankakee and State of Illinois, have invented a new, original, and ornamental Design for Gas Stoves, of which the following is a specification, reference being had to the accompanying drawing, forming part hereof.

The figure is a perspective view of a gas stove, showing my new design.

The design is especially characterized by the provision of an upstanding rear guard for the stove top with an upper edge of stepped formation conforming with the stepped formation of the upper edges of the panels of the front closure members, substantially as shown.

I claim:

The ornamental design for a gas stove, substantially as shown and described.

WILLIAM T. BRADBURY.
